UNITED STATES PATENT OFFICE.

ALBERT J. WILLIAMS, OF ROBERTSDALE, PENNSYLVANIA.

DESIGN FOR A GAME-BOARD.

45,211.

Specification for Design.

Patented Feb. 3, 1914.

Application filed August 13, 1913. Serial No. 784,636. Term of patent 3½ years.

To all whom it may concern:

Be it known that I, ALBERT J. WILLIAMS, a citizen of the United States of America, residing at Robertsdale, in the county of Huntingdon and State of Pennsylvania, have invented a new, original, and ornamental Design for Game-Boards, of which the following is a specification, reference being had to the accompanying drawing, forming part thereof.

The figure is a front elevation of a game board, illustrating my new design.

I claim:

The ornamental design for a game board, as shown.

ALBERT J. WILLIAMS.

Witnesses:

ALBERT FOARE,
RALPH R. WILLIAMS.
